UNITED STATES PATENT OFFICE.

OTTO S. THAL, OF SAN FRANCISCO, CALIFORNIA.

ADVERTISING DEVICE.

1,120,345.

Specification of Letters Patent.

Patented Dec. 8, 1914.

Application filed August 20, 1913. Serial No. 785,744.

To all whom it may concern:

Be it known that I, OTTO S. THAL, a citizen of the United States, residing in the city and county of San Francisco and State of California, have invented new and useful Improvements in Advertising Devices, of which the following is a specification.

This invention relates to electrical apparatus, and particularly to an electrical novelty adapted for use as an advertising device.

The present invention comprises the combination of electrical elements in such coordination and with such properties that the expansion of certain of the parts, due to the heat generated by the transmission of an electrical current therethrough, is utilized for the propulsion of a movable member or members.

20 In practising my invention I have found that, by utilizing parallel or concentric electric conductors and connecting the same to a source of electrical current, when a cylindrical or spherical body was placed upon the edges of the parallel or concentrically arranged conductors, the transmission of the currents from one of the conductors to the other being through means of said movable part or member, that that part of the conductors momentarily contacting with the movable transmitting device or connection becomes heated, due to the resistance of flow to the electrical current, and causes the parallel or concentric conductors which may be termed "rails" to expand. This forms in their edges convex or inclined ridges with the result that when the movable connection is spherical or cylindrical it will roll away from the momentarily expanded and convex edges of the conductors or rails. Since the movable member forms the circuit closer between the main conductors or rails, it is manifest that the movement of the circuit closing device constantly changes the portions of the edges of the rails where the resistance is greatest, and this constant change of position of the resistance portions of the rails results in the constant movement of the movable circuit closer along the rails 50 upon which it rests.

This apparatus I have utilized in practice and in the present case disclose it as embodied in an advertising novelty, with the object in view of providing an apparatus which to the uninformed presents a rather interesting and puzzling phenomenon be-

cause of the fact that the electrical connections are sealed. Since no apparent means are provided for propelling the movable circuit closer over the edges of the rails, a very effective device is provided for attracting and holding the attention of the general public, or those to whom the device may be exhibited, and this interest may be taken advantage of by providing elements of an advertising character in conjunction with the apparatus.

The invention consists of the parts and the construction and combination of parts as hereinafter more fully described and claimed, having reference to the accompanying drawings, in which—

Figure 1 is a plan view showing one embodiment or configuration of the rails and indicating the electrical connections. Fig. 2 is a cross section through one set of rails. Fig. 3 is a cross section through a set of rails, with a crank truck movable thereon. Fig. 4 illustrates diagrammatically the expansion of a portion of an edge of one of the rails when energized.

A simple embodiment of my invention is illustrated as comprising concentric rails 2 and 3 which, preferably, have high electrical resistance and are indicated as of comparatively thin sheets or strips which may be arranged horizontally or vertically and are insulated from each other by a tie connection 4. Since the rails 2 and 3 are preferably of a high resistance nature they may be energized by having suitably attached thereto better conductors, such as copper rings 5, sealed in the insulating ring and spacer 4; the copper rings being electrically connected to a source of current, as a battery 6. The electrical circuit through the parallel or concentric rails, as the case may be, is completed by mounting on the rails a movable circuit closer, as 7, Figs. 1 and 2, or which may be in the nature of a cylinder 90 or truck with wheels 8, Fig. 3, connected by a crank shaft 9. The rolling or movable member 7, when placed on the rails 2 and 3, will immediately close the electrical circuit, and since the rolling member 7 will bear 100 upon the rails at opposite points therein, and due to the relatively small area of the contact points, as between the rolling member and the rails, the latter will become heated, due to the resistance of the flow of electrical current. This will result in a slight expansion, forming a convexly curved edge 10,

Fig. 4, from which the rolling unstable circuit-closing member 7 will naturally move away in one direction or the other which will be determined by the direction of motion which it automatically takes or may be given.

By having the rail members 2 and 3 connected to a source of electrical current and then by adjusting the circuit closer 7 upon 10 the edges of the rails and thus closing the circuit, the heat generated in the rails at the points of contact with the rolling circuit closer will expand the edges of the rails. As the ball or rolling circuit closer moves down 15 the inclined surfaces of the expanded portions the point of contact, as between the circuit closer and the rails, is automatically changed and the zone of heat generated by the resistance automatically follows along 20 the rails in the line or direction of movement of the circuit closer 7; the latter being then automatically propelled along without any apparent application of force.

In Fig. 3 there is shown a circuit closer 25 which consists of the wheels 8 connected by a crank-shaft 9, and the rotary movement of the crank-shaft may be utilized to impart motion to a reciprocating device 9' on the circuit closer, thus increasing the interest of 30 the apparatus.

It is understood that I may arrange the parallel or concentric conducting rails 2 and 3 in any given or desired configuration so that they may be made in symbolical form 35 or may be arranged in the form of letters or geometrical figures. In Fig. 1 I have shown one set of tracks 2 and 3 in circular form, and in these are disposed other sets of tracks 11 which are appropriately electrically connected 40 with the outermost tracks 2-3 and the battery 6. Upon the sets of tracks 11 there may be disposed respective circuit closing devices 7 which may be of suitable construction and variously colored or lettered 45 as will serve the ends in view.

The utility of the apparatus as an advertising device can be further enhanced by providing such devices as will be operable by the moving circuit closer 7, such, for 50 instance, consisting in rocker shafts 12 each having a portion 13 lying in the path of its respective circuit closer 7, whereby, upon contact therewith, the rocker shafts will be actuated and thus lift or expose an advertising disk or sign 13'.

If desired, any electrical device 20 may be connected in series, or otherwise, the circuit of which would be closed when the part 7 traverses its connection at the track.

Having thus described my invention, what I claim and desire to secure by Letters Patent is—

1. An advertising device comprising a

substantially horizontal track consisting of electrical conductors, a source of electrical supply connected to said conductors, and a means for closing the circuit between the conductors comprising a device engageable with the edges of the conductors and movable therealong automatically by the progressive expansion of the edges of the conductors when the circuit is closed across the track by said moving means.

2. An advertising device comprising a substantially horizontal track consisting of 75 electrical conductors, a source of electrical supply connected to said conductors, a means for closing the circuit between the conductors comprising a device engageable with the edges of the conductors and movable therealong automatically by the progressive expansion of the edges of the conductors when the circuit is closed across the track by said moving means, and mechanical devices adapted to be actuated by said device during its movement.

3. An advertising device comprising a substantially horizontal track consisting of electrical conductors, a source of electrical supply connected to said conductors, a 90 means for closing the circuit between the conductors comprising a device engageable with the edges of the conductors and movable therealong automatically by the progressive expansion of the edges of the conductors when the circuit is closed across the track by said moving means, and electrical devices controlled by said device during its movement.

4. An advertising device including substantially horizontal spaced conducting elements having connection with a source of electrical supply, and means on said elements for closing the circuit therebetween and movable therealong by the progressive 105 expansion of the elements as the circuit is closed by said means.

5. An advertising device including substantially horizontal spaced conducting elements having connection with a source of 110 electrical supply, means on the elements for closing the circuit therebetween and movable therealong by the progressive expansion of the elements as the circuit is closed by said means, and means movable independent of the first named means and actuated by the movements of the latter for attracting the attention of observers.

In testimony whereof I have hereunto set my hand in the presence of two subscribing 120 witnesses.

OTTO S. THAL.
